UNITED STATES PATENT OFFICE.

ARTHUR RICE, OF NEW ALBANY, INDIANA, ASSIGNOR TO THE PEERLESS MANUFACTURING COMPANY, OF LOUISVILLE, KENTUCKY.

SAND-MOLDING MACHINE.

SPECIFICATION forming part of Letters Patent No. 353,712, dated December 7, 1886.

Application filed May 17, 1886. Serial No. 202,571. (No model.)

To all whom it may concern:

Be it known that I, ARTHUR RICE, a citizen of the United States, residing at New Albany, in the county of Floyd and State of Indiana, have invented certain new and useful Improvements in Sand-Molding Machines, of which the following is a full, clear, and exact description.

This invention relates to a machine for forming sand molds for casting iron and other metallic articles; and the present invention is a modification of the machine covered in the United States Patents Nos. 322,202, 332,834, and 340,362; and the invention consists in a sand-molding machine in which the pattern and its bed are stationary and rigidly affixed to an immovable member of the machine, combined with a moving flask, substantially as hereinafter particularly set forth and claimed.

In the accompanying drawings, in the several figures of which like parts are similarly designated, Figure 1 is a perspective view of my machine in the position of compressing. Fig. 2 is a similar view, with the binder swung aside ready to receive a fresh flask. Fig. 3 is a side view of a modification, wherein the "draw" is at an angle. Fig. 4 is a vertical section with the parts in position to begin compressing or remove a molded flask. Fig. 5 is a similar view taken at right angles to the view in Fig. 4. Fig. 6 is a vertical section of the parts in the position of Fig. 1. Fig. 7 is a perspective view of a one-piece pattern and pattern-bed; and Fig. 8 shows, in perspective, details of the false part and flask. Fig. 9 shows the improved cope and drag in perspective.

The frame-work *a* is of approved construction to receive a main driving-shaft, *b*, to which power may be applied from a band-wheel, *c*, through a counter-shaft, *d*, worm *e* thereon, and worm-wheel *f* on the main shaft.

The parts in this machine corresponding with like parts in the machine illustrated in the Patent No. 322,202 are herein similarly designated.

q is the box or "false part," provided with the rigidly-affixed depending shanks *r*, which have vertical movement in the guideways *s* on the sides of the frame-work. The false part is provided with pitman-rods *t*, which in this in-

stance are connected eccentrically to the worm-wheel *f* on one side and a disk or crank, *f'*, on the other side. (See Figs. 4 and 6.) Obviously the rotation of the shaft *b* will alternately raise and lower the false part on the bearings it has on the rabbeted portions *p* of the frame-work. The half-flask *v* is of usual construction.

In Figs. 1, 2, and 3 the binder *y* is constructed and applied substantially as in the Patents Nos. 332,834 and 340,362, and in Figs. 4, 5, and 6 the binder is constructed and applied substantially as in the Patent No. 322,202, and need not be herein further set forth.

For starting and stopping the machine I may employ a friction-clutch of any approved construction (but not shown in detail herein) in connection with the band-wheel *c*, which latter is loose on the shaft *d*, and this clutch may have a rod, *g*, which is jointed by a bevelled-head pin, *g**, to the lever *j*, the latter being pivoted to the frame of the machine. A lever, *h*, is pivoted to the guide *s*, and has a forked end, *h'*, the upper and lower members of which forked end are periodically engaged by a pin, *i*, on the shank *r* of the false part as said false part is raised and lowered to vibrate said lever. The lower end, *h''*, of the lever *h* is hinged to it by a pin, *h'''*, at right angles to the pivot-pin of said lever, so that said end is free to swing outward from the lever *h*. Now, the machine having been started by the manual operation of the clutch through the rod *g* and lever *j*, as the shank *r* descends on the down (compressing) stroke, the pin *i* strikes the lower fork of the lever *h*, and its end *h''*, then coming against the square back of the pin *g**, forces the rod *g* out and stops the machine at the compressing-point, and passes beyond and out of reach of the said pin to the position indicated by dotted line *x'*, Fig. 2. This operation

is possible by reason of the fact that the levers *j* and *h* have different centers of motion or pivots, and that their ends move in arcs of different and eccentric circles. It will be seen, therefore, that the end *h''* will travel in an arc substantially parallel with the arc of the lever *j* for only a given distance, and then leave such arc, and in so doing slip by the squared back of pin *g** into the position indicated by dotted

line x' . At the proper time the rod g is again manually operated to start the machine to permit the complete downstroke without the pin further acting upon the forked lever h . The 5 downstroke being completed and the upstroke begun, the lever h remains at the dotted-line position until the pin i passes the fulcrum of the lever h , when it acts upon the upper end of the fork of the lever, and drives said lever 10 into the full-line position again, its hinged end h'' yielding to pass over the beveled side of the head of the pin g'' .

Instead of the partly automatic operation of the clutch, the said clutch may be actuated 15 wholly by hand, as by such an arrangement as is shown in Fig. 1, which is simply a spring hand-lever, j , connected to the clutch-rod g .

The pattern k , Figs. 4, 5, 6, and 7, is shown 20 as purely conventional, and may be, and is here shown as, one with its bed l , which bed rests solidly upon and is affixed to the upper edge of the frame-work, as by bolts or screws. No templet is employed; but the pattern is used not only to form the mold in the sand as 25 the flask is brought down by the false part and pitmen, but it and its bed serve as a base, against which the sand is compressed. This is the distinguishing characteristic difference between my present invention and that covered by the Patent No. 322,202, and it greatly 30 simplifies the construction of parts, the machine at the same time losing little, if any, of its effectiveness and utility for many kinds of work.

35 In Fig. 3 I have shown my machine in compressing position, arranged to draw at an angle instead of straight, as in the other views. This arrangement is desirable in some classes of work—as, for example, in molding plow-points, which have an "undercut," so called in the founder's art, or a re-entrant angle. In this form of machine the recessed or rabbeted end of the frame-work a slants at the desired angle. The false part slants correspondingly, 40 and the shanks project from it at a corresponding angle, and work in guides properly arranged to receive them. The pitmen follow the same slant, all as clearly represented in said Fig. 3.

45 Fig. 4 illustrates the parts in the position to begin compressing, the parts also being in substantially this position when the binder is swung aside, as in Fig. 2, for introducing the sand into an empty half-flask or for removing 50 a mold.

55 Figs. 1 and 6 show the parts in position when the sand is compressed, or, in other words, when the mold is formed. The three Figs. 4, 5, and 6 illustrate the same form of machine as that shown in the Patent No. 322,202, but equipped with the present invention.

The operation of molding with this machine is as follows: To receive the flask the parts are brought to the position shown in Figs. 2 and 65 4, the top of the box or false part q being in practice about an inch and a half above the

surface of the pattern-bed, so as to furnish space for the surplus sand needed to fill the flask, while compensating for compression. The binder is then thrown around out of the 70 way, as in Fig. 2, and an empty half-flask secured upon the upper part of box q . The half-flask is then loosely filled with properly-tempered sand and the binder swung back and secured over the flask, as in Figs. 1, 3, 4, 5, and 75 6. The shaft b is now rotated through the band-wheel c , counter-shaft d , worm e , and worm-wheel f , and through the intervention of the pitmen t the parts (binder, flask, and false part or box) are drawn down to the full 80 downstroke, bringing the lower edge of the flask down flush with the pattern-bed, and causing the pattern to embed itself in the sand, it and the bed compressing the sand and forming the mold. By the further revolution 85 of the shaft b the false part, flask, and binder rise together, thereby stripping the mold from the stationary pattern, and leaving the mold finished in the flask and the flask ready to be removed. At the completion of the upstroke 90 the parts are in the position indicated in Fig. 4, and then the binder may be released and the half-flask containing the finished mold removed. Further revolution of the shaft b carries the box q and its appurtenances to the position indicated in Fig. 2, thereby setting the machine for another flask. 95

The up and down movement of the flask and box q is, in practice, say, from two to six inches, (more or less,) to allow for the necessary 100 depth of the pattern, only about an inch and a half of the last part of the downstroke, however, being necessary to compress the sand in the flask.

The same advantages are gained in this machine to about the same degree as in the machine set forth in the Patent No. 322,202. 105

Fig. 8 represents the movable box q arranged for stationary guide-pins to be used instead of adjustable pins and sockets, as heretofore used. The practice has been to have in the movable box q (at or about where socket is shown at 1) sockets for the reception of the pins of the cope. When molding drags, pins were fitted in these sockets and extended above the 110 movable box the length of the ordinary flask-pin. The drag would fit to these pins. By having stationary pins fixed in the movable box at 2, and holes to fit drilled in both cope and drag at 3 and 5, respectively, every half-flask will fit the movable box. 115

In order to make drags and copes fit with each other, holes are drilled at 4 in the drag, and the cope is provided with pins 6, to engage said holes. In the movable box, at 1, 120 holes or recesses are cut to accommodate the cope-pins, but have nothing to do with making the fit to the movable box; in fact, the whole lug might be removed beyond the pins 2 without detriment to the fit of the flask to the box. 130

In the other figures of the drawings the connection of the flask and false part may be

taken as old and common, or else purely conventional.

It will be noticed that in Fig. 1 I omit and dispense with the parts *h i*, and rearrange the 5 rod *g* and the lever *j* to effect the starting and stopping of the machine.

What I claim is—

1. In a sand-molding machine of substantially the character set forth, a movable false 10 part provided with a binder and carrying the flask, and a stationary pattern and pattern-bed, in relation to which the flask is moved to make and clear the mold, substantially as described.

2. In a sand-molding machine, the combination of a frame-work, a stationary pattern, and pattern-bed fixed to the frame-work, with a movable false part carrying a binder and surrounding said pattern and bed, guided upon the frame-work, and adapted to receive and 20 hold a flask and move it down upon the pattern and its bed, and remove it therefrom, as set forth, to thereby form the mold, compress the sand, and strip the mold from the pattern, substantially as described.

25 3. In a sand-molding machine, the combination of a stationary pattern and pattern-bed, with a false part surrounding them and adapted to receive a flask, guides for said false part, means, substantially as described,

for imparting up and down movements to said 30 false part with relation to the pattern and pattern-bed, and a binder connected to said false part and constructed to cover the flask and secure it to the false part, substantially as specified.

35 4. In a sand-molding machine, the frame-work having its upper end rabbeted and slanting, a pattern and pattern-bed, a slanting false part or box arranged thereon and guided thereby, and means, substantially as described, 40 to impart up and down movements to said false part on said slanting rabbeted portion of the frame-work, combined with a flask and binder, whereby the draw may be effected at an angle, substantially as described. 45

5. In sand-molding apparatus provided with notches 1 and pins 2, a drag having holes 3 and 4, and a cope having holes 5 and pins 6, to adapt the drag and cope to each other and to the notches and pins of the apparatus, substantially as described. 50

In testimony whereof I have hereunto set my hand this 13th day of May, A. D. 1886.

ARTHUR RICE.
